TURNSTILE

Rudolph F. Kelker, Jr., Evanston, Ill.

Application May 13, 1939, Serial No. 273,471

3 Claims. (Cl. 39—3)

This invention relates to gates of the turnstile type, and more specifically to a twin gate structure of such type.

Gates comprising turnstiles rotatable only one way are familiarly employed for controlling exits from subways and other premises where it is desired to prevent entrance through the exits. In connection with the installation of such gates, the matter of space consumption is an important item. This is particularly true in the case of subway stations, where ground area is expensive and where the cost of an exit structure, including foundation, floor and roof or other overhead structure, depends largely upon the number of cubic feet in the structure.

In many situations the available width of space for exits is restricted, so that whether or not turnstiles may be utilized in sufficient number for reasonably convenient accommodation of traffic during busy periods will depend upon whether they can be placed in such restricted width of space.

Having in view, therefore, the desirability of space conservation in a plurality of turnstile gates, I have provided a twin gate structure wherein two turnstiles occupy only about two thirds of the space or substantially less space than would ordinarily be required for two turnstile gates; with the effects, among others, of making possible important savings in construction costs of exit structures, as well as permitting utilization of such twin gate structure in locations too narrow for two ordinary turnstile gates.

Further advantages of a structure embodying the invention are that it is convenient in use, and of practicable and economical character, the amount of construction materials required therefore being somewhat less than would ordinarily be required for the construction of two turnstile gates.

The nature of the invention will be best understood by reference to an illustrative embodiment thereof shown in the accompanying drawing.

In said drawing:

Fig. 1 is a horizontal section of one illustrative structure embodying the invention, such section being taken on the line 1—1 of Fig. 2 and revealing a plan of the two turnstiles with their respective cage sections and interposed barrier structure.

Fig. 2 is a front elevation of the structure shown in Fig. 1.

Fig. 3 is a horizontal section view of another illustrative structure embodying the invention.

Figs. 4 and 5 are views of different forms of barrier structures which may be used, for example, in place of the barrier structure shown either in Fig. 1 or in Fig. 3.

It will be understood that the following description with reference to the specific structures selected for illustration is not to be taken as limiting the invention thereto nor otherwise than as defined by the claims appended to the description.

Referring to the illustrative structure shown in Figs. 1 and 2, twin turnstiles are here represented by the rotatable posts 10 and 11 carrying the radiating horizontally disposed arms 12 and 13 respectively; the arms of each turnstile being arranged to provide a series of revolving baffles, each baffle comprising a set of such arms one above another. The baffles of the respective turnstiles sweep through the respective pedestrian passages 14 and 15 between the centers of the turnstiles and the cage segments 16 and 17 associated therewith. The two turnstiles may be independently freely rotatable in opposite directions, permitting the passage of pedestrian traffic in two files or lines. To prevent reverse rotation of the turnstiles, they may be provided with any appropriate ratchet means, as is well understood in the art. Assuming the two lines of traffic to be passing through the gate structure in the directions indicated by the arrows, the entrance ends of the respective traffic passages are between the three spaced fixed posts 18, 19, 20, and the exit ends of such passages are between the three spaced fixed posts 21, 22, 23.

It will be observed that the illustrative structure comprises confronting cage sections whose ends at the fixed posts 18, 20 and 21, 23 are spaced apart only about twice the width of a single pedestrian passage, while the space between the cage sections is occupied by the two turnstiles which are in interlapping juxtaposition; the centers of the turnstiles being spaced apart a distance substantially less than the diameter though greater than the radius of an individual turnstile.

As shown more clearly in Fig. 2, the planes of revolution of the baffle arms 12 of one turnstile are in staggered relation to or offset from the planes of revolution of the baffle arms 13 of the other turnstile. Thus the two turnstiles have intermingling portions in the sense that their respective arms, by virtue of their interjacent arrangement as shown in Fig. 2, traverse a space common to the two turnstiles.

Guarding the space traversed in common by the arms of the two turnstiles is a fixed grill-

like barrier structure, represented in this instance by the posts 19 and 22 and connecting pairs of horizontal ribs or bars 24, said pairs of bars 24 being arranged one above another and suitably spaced to permit arms of the respective turnstiles to pass through the interstices between the bars, as, for example, in accordance with the arrangement shown in Fig. 2. As represented in Fig. 1, the barrier structure is of generally diamond form in horizontal section. Such type of barrier structure may be of various specific forms or constructions. For example, the pairs of horizontal barrier bars shown in Figs. 1 and 2 might be replaced by pairs of elements such as shown in 25 in Fig. 4, these elements being carried one above the other by the posts 19 and 22. As shown in Fig. 5, the pairs of bars of a barrier structure of the form shown in Fig. 1 may be connected by cross braces 26. Still another barrier structure of generally similar character but different form is shown in Fig. 3.

In the structure shown in Fig. 1, the arms of each turnstile are arranged to provide three radiating baffles spaced 120 degrees apart, as is desirable to facilitate the passing of pedestrian traffic through the gate structure, the angular spaces between the baffles being ample to allow pedestrians carrying handbags to pass through the structure between the revolving baffles without being hit by the following baffles. The arrangement shown in Fig. 1 is also especially desirable for compactness since it permits the centers of the two turnstiles to be spaced apart a distance only slightly greater than a turnstile radius.

The gate structure shown in Fig. 3 is similar in principle to that already described. In Fig. 3, the parts corresponding to those in Figs. 1 and 2 are the two turnstiles comprising rotary posts 110 and 111, carrying the radiating baffle arms 112 and 113; said turnstiles being in interlapping juxtaposition as already explained, and occupying the space between the cage segments 116 and 117; and the space traversed in common by the interjacent arms of the two turnstiles being guarded by a grill-like barrier structure. Said barrier structure in Fig. 3 comprises diverging pairs of arms or bars 124 carried one above another by the posts 119 and 122. In the construction shown in Fig. 3 the radiating arms of the turnstiles are arranged to provide four baffles for each turnstile, the centers of the two turnstiles being spaced somewhat further apart than in Fig. 1 but a substantially less distance apart than the diameter of an individual turnstile.

Either of the structures represented in Figs. 1 and 3 occupies substantially less ground area and width of corridor space than would be required for two ordinary turnstile gates; the saving of space being in the case of Fig. 1 about one-third and in the case of Fig. 3 about one-fourth; or in other words the structure of Fig. 1 is only about one and one-half times as broad as a single turnstile gate, and that of Fig. 2 only about one and three-fourths as broad as a single turnstile gate. The installation of either of the structures requires somewhat less construction material

than ordinarily required for two turnstile gates. The structure is convenient and attractive in use, permitting persons walking side by side to pass close to one another through the two turnstiles.

5 The invention does not depend upon specific mechanical forms or details of construction of the turnstiles and correlated parts, and may be applied to structures in which the turnstiles are rotatable either in one direction, both directions, 10 or in only the opposite directions, to suit different requirements and conditions as to traffic to be controlled.

I claim:

1. A twin gate structure comprising confronting cage segments, a pair of interlapping turnstiles occupying the space therebetween, said turnstiles comprising radiating arms in interjacent planes, and an interposed barrier structure comprising posts in front and rear of the interlapping portions of said turnstiles and superposed barrier bars carried by and extending between said posts in planes interjacent with the planes of revolution of the turnstile arms, said barrier bars and posts forming a barrier structure gradually increasing in width from the posts to the transverse center of the gate structure and substantially occupying the space traversed in common by the two turnstiles, said turnstiles being centered adjacent to the opposite sides of 30 the widest portion of said barrier structure.

2. A twin gate structure comprising confronting cage segments, a pair of interlapping turnstiles occupying the space therebetween, said turnstiles comprising radiating arms in interjacent planes, and an interposed barrier structure comprising posts in front and rear of the interlapping portions of said turnstiles and barrier bars arranged in superposed pairs carried by and extending between said posts, the barrier bars 35 of said pairs diverging from said posts to the transverse center of the gate structure and arranged in planes interjacent with the planes of revolution of the turnstile arms, said turnstiles being centered adjacent to the opposite sides of the widest portion of said barrier structure and the latter substantially enclosing the space traversed in common by the arms of the two turnstiles.

3. A twin gate structure comprising confronting cage segments, a pair of interlapping turnstiles occupying the space therebetween, said turnstiles comprising radiating arms in interjacent planes, and an interposed barrier structure comprising posts in front and rear of the interlapping portions of said turnstiles and superposed barrier bars carried by and extending between said posts and diverging therefrom to the transverse center of the gate structure and arranged in planes interjacent with the planes of 50 revolution of the turnstile arms, said turnstiles being centered at opposite sides of the widest portion of said barrier structure and the latter substantially enclosing the space transversed in common by the arms of the respective turnstiles, 55 the centers of the turnstiles being outside of the barrier structure.

RUDOLPH F. KELKER, JR.
